UNITED STATES PATENT OFFICE.

FORD W. HARRIS, OF LOS ANGELES, CALIFORNIA, ASSIGNOR TO PETROLEUM RECTIFYING COMPANY OF CALIFORNIA, OF LOS ANGELES, CALIFORNIA, A CORPORATION OF CALIFORNIA.

INLET BUSHING FOR ELECTRICAL DEHYDRATORS.

Application filed May 14, 1924. Serial No. 718,373.

To all whom it may concern:

Be it known that I, FORD W. HARRIS, a citizen of the United States, residing at Los Angeles, in the county of Los Angeles, State 5 of California, have invented a new and useful Inlet Bushing for Electrical Dehydrators, of which the following is a specification.

My invention relates to electrical dehydrators such as are used in treating emulsions of petroleum oil and water for the purpose of separating the water from such emulsions. In the treatment of oil by such an apparatus it is necessary to provide a container which is preferably entirely enclosed so that the escape of oil vapors therefrom can be prevented. It is also necessary to conduct electricity through the walls of this container to suitable treating apparatus placed therein.

In the treatment of petroleum emulsions it is extremely common to use potentials of about 10,000 volts, and the problem of providing means for conducting electricity at 15 this potential through the walls of the container is a serious one. It is common practice to provide inlet bushings which may be made of porcelain or composition material, these bushings being secured in the wall of 20 the container and projecting therein.

Natural petroleum emulsions contain water, sand and certain other mineral matter in suspension. It has been found that in the treatment of petroleum emulsions 25 there is a tendency for the sand and other foreign matter to settle on the surface of the insulating bushing inside the container. Such material may, especially when wet, be a moderately good conductor of electricity 30 with the result that conducting paths are formed on the surface of the insulator which tends to short-circuit the apparatus and which in many cases injure the insulator either by burning or cracking it. It is an 35 object of my invention to provide a means by which the insulating qualities of such bushings may be maintained even where a very dirty oil is being treated.

Further objects and advantages will be 40 made evident hereinafter.

Referring to the drawing which is for 45 illustrative purposes only,—

Fig. 1 is a sectional elevation through a

portion of an electrical dehydrator to which my invention has been applied.

Fig. 2 is a plan view thereof.

In the form of the invention shown, 11 is the roof or top of the tank in which the treatment is taking place. Secured therein, preferably by welding at 12, is a vertical cylinder 13 which forms a gas pocket 15. A porcelain or composition bushing 20 has a metal flange 21 secured thereon, this flange being secured by welding at 22 to a plate 23 which is secured by means of bolts 24 to the top of the cylinder 13. The insulator 20 may consist of a cylinder 30 having skirts 31 either formed or secured thereon. Secured to the top of the insulator 20 is a metal cap 33. A conductor 40 extends 70 downwardly through the metal cap 33 and through a central opening 41 in the insulator 20 extending down into the interior of the container. Packing 45 is placed around the conductor 40 where it passes through the metal cap 33, this packing being compressed by a gland 46, the metal cap 33 and the gland 46 with the packing 45 forming a stuffing box which prevents the escape of gas or other fluid around the conductor 40.

Also secured in the cover 11 is a second cylinder 50 which encloses a float chamber 51. Threaded on the upper end of the cylinder 50 is a valve body 52. In the upper end of the valve body 52 a closed nipple 53 is threaded and a cap 54 is threaded on the top of the closed nipple. A float 60 is placed inside the float chamber 51, being connected by a valve stem 61 with a valve 62, which closes an opening 63 through the valve body 52 when the float is in its lower position, as shown. A gas inlet pipe 70 connects through the cap 54 with the space above the valve body 52, this gas inlet pipe 70 being supplied with natural gas under 95 pressure from a high pressure gas line 71 through a ball check valve 72.

The method of operation of my invention is as follows: Prior to filling the container, the parts are in the position shown in Fig. 1. As the container is filled the emulsion tends to rise therein until it reaches the lower end of the gas pocket 15 and the float chamber 51. These float chambers being entirely enclosed, except for the gas inlet 105 pipe 70, the air which is contained therein

is trapped but may be slightly compressed due to whatever pressure is put upon the container. The float chamber 51 and the gas pocket 15 are connected by means of a connecting pipe 80. The gas in the high pressure gas line 71 is at a considerably higher pressure than is ever used inside the container. If for any reason, such for example as leakage from the stuffing box, fluid 10 rises in the gas pocket the pressure between the gas pocket and the float chamber will equalize through the pipe 80 and the level of fluid in the float chamber is correspondingly increased, the level of the fluid in the 15 two chambers being at all times maintained constant since the gas pressure in the two chambers is exactly equal and the liquid therein naturally tends to seek its own level. If for any reason the liquid in the lower 20 end of the gas pocket and the float chamber rises to such a degree that it tends to wet the lower end of the insulator 20, the float 60 is at the same time sufficiently raised to lift the valve 62 from its seat and to admit 25 high pressure gas to the float chamber 51 through the pipe 70 and to the gas pocket 15 through the pipe 80. This gas under pressure tends to force the liquid in the bottom of the gas pocket and the float chamber 30 downwardly until the float 60 falls to a sufficient degree to close the opening 63 and thus shut off a fresh supply of gas.

It will be seen that as long as the pressure in the high pressure gas line 71 is 35 above the pressure inside the container, gas is maintained in the gas pocket 15 to a sufficient degree to prevent the liquid from covering or touching the outer surface of the insulator 20. If the outer surface of 40 this insulator is clean to begin with, it is maintained in a clean condition so that short-circuiting paths cannot be formed thereover.

By the use of my invention it is therefore 45 possible to maintain the insulating valve of the insulating bushing even where very dirty or wet emulsion is being treated.

I claim as my invention:

1. In combination: a container adapted to 50 contain an electrically conducting liquid; an electric insulating bushing projecting into said container; walls forming an enclosed pocket about a portion of that portion of the insulator which is inside said container; and means for supplying gas in said pocket.

2. In combination: a container adapted to 55 contain an electrically conducting liquid; an electric insulating bushing projecting into said container; walls forming an enclosed pocket about a portion of that portion of the insulator which is inside said container; an inlet pipe for supplying gas to said pocket; and means for shutting off 60 the supply of gas whenever the level of the

liquid in said pocket falls below a predetermined level.

3. In combination: a container adapted to contain an electrically conducting liquid; an electric insulating bushing projecting 70 into said container; walls forming an enclosed pocket about a portion of that portion of the insulator which is inside said container; an inlet pipe for supplying gas to said pocket; a valve controlling the flow 75 of gas through said inlet pipe; and means for closing said valve whenever the level of oil in said pocket reaches a predetermined point.

4. In combination: a container adapted 80 to contain an electrically conducting liquid; an electric insulating bushing projecting into said container; walls forming an enclosed pocket about a portion of that portion of the insulator which is inside said container; an inlet pipe for supplying gas to said pocket; a valve controlling the flow 85 of gas through said inlet pipe; and a float for closing said valve whenever the level of oil in said pocket reaches a predetermined 90 point.

5. In combination: a container adapted to contain an electrically conducting liquid; an electric insulating bushing projecting 95 into said container; walls forming an enclosed pocket about a portion of that portion of the insulator which is inside said container, said pocket being in open communication with the interior of the container at its lower end; walls forming a float chamber upon the same horizontal level as said pocket, said chamber having its lower end in open communication with said pocket and its upper portion in open communication with said pocket; and means for automatically regulating the level of liquid in 100 said pocket.

6. In combination: a container adapted to contain an electrically conducting liquid; an electric insulating bushing projecting 110 into said container; walls forming an enclosed pocket about a portion of that portion of the insulator which is inside said container, said pocket being in open communication with the interior of the container at its lower end; walls forming a float chamber upon the same horizontal level as said pocket, said chamber having its lower end in open communication with said pocket and its upper portion in open communication with said pocket; a gas supply pipe delivering gas under pressure to said chamber; valve means closing said gas supply pipe; and means for closing said valve whenever the oil level in said chamber falls below 115 a predetermined level.

7. In combination: a container adapted to contain an electrically conducting liquid; an electric insulating bushing projecting 120 into said container; walls forming an en-

closed pocket about a portion of that portion of the insulator which is inside said container, said pocket being in open communication with the interior of the container at its lower end; walls forming a float chamber upon the same horizontal level as said pocket, said chamber having its lower end in open communication with said pocket and its upper portion in open communication with said pocket; a gas supply pipe deliver-
5 ing gas under pressure to said chamber; valve means closing said gas supply pipe; and a float in said float chamber adapted to close said valve whenever the oil level in said chamber falls below a predetermined 15 level.

In testimony whereof, I have hereunto set my hand at Los Angeles, California, this 7th day of May, 1924.

FORD W. HARRIS.
